ANCHOR BAND FOR CORSETS OR THE LIKE

Jane T. Buhrlie, Great Bend, Kans.

Application August 10, 1939, Serial No. 289,415

2 Claims. (Cl. 241—1)

My invention relates to anchor bands for corsets or the like, and has for its principal object to retain a corset in its fitted position.

A further object of my invention is to provide a substitution for hose that are commonly employed as an anchor and adapted to tension the lower extremity of the corset or girdle, as the case may be, to its normal fitting position.

A still further object of my invention is to provide a band having means to adjust the same longitudinally whereby thighs varying in size may be comfortably fitted, the band being detachably connected to the corset, inexpensive to produce and efficient in its performance.

These and other objects will hereinafter be more fully explained, reference being had to the accompanying drawing forming a part of this specification, in which like characters will apply to like parts in the different views.

Referring to the drawing:

Fig. 1 represents a human form to illustrate the application of the invention.

Fig. 2 is an outer side view of the band prior to encircling the same.

Fig. 3 is an inside view of Fig. 2.

Fig. 4 is an enlarged view of Fig. 2 modified with respect to its connections with hose supporting straps.

Fig. 5 is an enlarged side view showing the upper extension as pendants engaged by the corset hose supporting straps.

Fig. 6 is a modification for the connection of the hose supporting strap.

Fig. 7 is an enlarged edge view of Fig. 6, partly in section.

Fig. 8 is a side view illustrating the longitudinal adjustments for the band.

Fig. 9 is an upper edge view of Fig. 8.

Fig. 10 is an upper plan view of the band as encircled.

My invention herein disclosed consists of an elastic band 1 to engage peripherally of the thigh with a comfortable fit, said band being arced edgewise as at A and B, respectively, to conform to the divergence of the thigh whereby an upper movement of the band will be avoided, said edge portions preferably being ornamented by a lace and stitched thereto, and the said band is equipped with a plurality of hooks 2 and eyes 3 spaced apart in their respective ends of the band as removable connecting means therefor as applied in working relation to the lower extremity of a corset or the like 4.

It will be seen that downwardly extending from the lower extremity of the corset is a

plurality of straps 5 connected thereto, each having a clasp consisting of loop element 6 carried by the strap a spaced distance upward from the lower end thereof. Said loop elements are preferably made of metal and adapted to engage over a ball element 7 of the clasp that is likewise secured near the end of said strap in working relation to the lower extremity of the reduced portion D of said loop element as securing means to a fabric upper extension 8 that is attached to and spaced apart along the upper edge of said band 1 as shown in Figs. 1, 2 and 3.

Being so arranged the fabric of the extension is placed over the ball and secured thereon by the loop element compressing the fabric to engagement with the neck, this being a conventional well known principle, and in lieu thereof as an alternate I have arranged a hook 9 secured to the band as illustrated in Figs. 6 and 7 through the medium of a tab 10 stitched to the band 15 on the outer side thereof in such position to avoid the upper extremity of the hook extending above the edge of the band, the hook adapted to engage with the said loop element 6.

20 In Fig. 8 is illustrated a plurality of rows of eyes, the rows spaced apart and to be engaged selectively by the said hooks 2 whereby the length of the band is varied as the case may require for a proper fit about the thigh of the wearer, and each of said rows of eyes are concealed by a flap 11 stitched to the band at each end and along one edge thereof, the other edge being free is means to enter the hook to engage with their respective eyes, being so arranged will conceal said hooks and eyes from view and also as a non-obstructive arrangement.

25 While I have shown and described specific clasps and extensions with which they engage and its specific method of varying the band, I do not wish to be restricted to such alone as each thereof may be varied or further modified as lie within the scope of the appended claims, and furthermore the band may be varied from its elastic nature to a non-elastic fabric or substance.

Having fully described my invention what I claim as new and desire to secure by Letters Patent is:

30 1. In anchor bands for corsets or the like, in combination, an elastic band of the class described for the thigh of a leg, the band prior to forming the same angularly being arcuate edgewise thereof to form a frusto-conical band to conform to the upper divergence of the thigh, a single row of hooks secured to the band ad-

jaçent one end thereof, a plurality of rows of eyes, the rows spaced apart, beginning at the other end of the band and secured thereto, the eyes of each row being spaced to correspond with the spacing of the hooks, a flap for each row of the eyes and having one edge and each end stitched to the band, whereby a pocket is formed and in which the eyes are concealed so that the row of hooks engaging with the rows of eyes, selectively, will likewise be enclosed in the pocket, by which means the annular band is adjustable for snug engagement on the thigh.

2. In anchor bands for corsets or the like, in combination, an elastic band of the class described for the thigh of a leg, the band prior to forming the same annularly being arcuate edge-wise thereof to form a frusto-conical band to conform to the upper divergence of the thigh, a two-part separable fastening means to connect

the ends of the band, there being a single row of one corresponding part of the fastening means secured to the band adjacent one end thereof and a plurality of rows of the other part of the fastening means, last said rows being spaced apart, beginning at the other end of the band and secured thereto, the last named parts of the fastening means of each row being spaced to correspond with the spacing of the parts of the 10 first said row, a flap for each row of last said parts and having one edge and each end stitched to the band, whereby a pocket is formed and in which the last said parts are concealed so that the row of first said parts engaging with the 15 rows of last said parts, selectively, will likewise be enclosed in the pocket, by which means the annular band is adjustable for snug engagement on the thigh.

JANE T. BUHRLE.
